DESIGN FOR A NOVELTY VEST FOR BOYS AND GIRLS

Harold Edward Radford, Toronto, Ontario,
Canada, assignor to Clifford Egbert Radford,
Chicago, Ill.

Application May 16, 1934, Serial No. 51,799
In Canada February 6, 1934

Term of patent 7 years

To all whom it may concern:

Be it known that I, HAROLD EDWARD RADFORD, a subject of King George the Fifth, residing in the city of Toronto, county of York, Province of Ontario, Dominion of Canada, have invented a new, original, and ornamental Design for a Novelty Vest for Boys and Girls, of which the following is a specification, reference being had to the accompanying drawing, forming part thereof.

Figure 1 is a front view and Figure 2 is a back view of a vest, ornamented with self fringe, bottom edge and pockets; and a larger fringe inserted at the junctions of the front and back sections and engaged by the stitching thereat.

I claim:

The ornamental design for a novelty vest for boys and girls as shown and described.

HAROLD EDWARD RADFORD.
